UNITED STATES PATENT OFFICE.

EDWARD KIRBY BOTTLE, OF ELMIRA, AND JAMES W. ANDERSON, OF NEW YORK, N. Y.,
ASSIGNORS TO AMERICAN SALES BOOK COMPANY, LIMITED, OF TORONTO, CANADA.

CHECK HOLDER.

Application filed February 2, 1925. Serial No. 6,160.

This invention relates to check holders and with respect to its more specific features to holders of the character referred to with which a punch is associated for convenient 5 operation upon a check removed from a pad retained on the holder.

One of the objects of the invention is the provision of a combined check holder and punch of simple and inexpensive construction 10 adapted to avoid injury to and displacement of the checks or the pad of checks when the instrument is in use.

Another object of the invention is the provision of a simple and practical combined check holder and punch which may be suspended from the person and conveniently and rapidly grasped for operation without injury to the operator.

Another object of the invention is the provision of a simple check holder adapted 20 without change to accommodate pads having either a small or a large number of checks and to utilize the pad in some measure to participate in retaining the punchings on 25 the instrument so as to avoid unsightliness occasioned when the punchings are permitted to scatter.

A further object of the invention is to provide a device of the character referred to 30 in which checks may be selectively marked by the punch either at their edges or at their middle portions within the edges.

Other objects will in part be obvious and will in part appear hereinafter.

The invention accordingly comprises an article of manufacture possessing the features, properties, and the relation of elements which will be exemplified in the article hereinafter described and the scope of 40 the application of which will be indicated in the claims.

For a fuller understanding of the nature and objects of the invention reference should be had to the following detailed description 45 taken in connection with the accompanying drawing, in which:

Figure 1 is a perspective view of a holder embodying the invention;

Fig. 2 is a longitudinal section thereof 50 with a pad of checks thereon;

Fig. 3 is a cross-section of Fig. 4 on line 3-3;

Fig. 4 is a section through the punch and die and showing the pad in position spaced 55 from the die plate;

Fig. 5 illustrates a holder, partly broken away, with a modified form of retainer.

Fig. 6 illustrates a modified form of the punching tongue;

Fig. 7 is a plan of a check as detached 60 from the pad in use;

Fig. 8 is sectional detail illustrating the punch.

Fig. 9 is a view similar to Fig. 1 illustrating the modified form of punching tongue 65 according to Fig. 6.

Referring now more specifically to the drawings, the check holding instrument illustrated in Figs. 1 to 4, includes a plate 1 adapted to be held in the hand and to serve 70 as a removable support for a pad 2, of connected paper checks. As customary, for instance in restaurant use, the pad is composed of a series of superposed checks having a staple 5 passing therethrough from 75 bottom to top to connect the checks together in pad relation. Each of the checks of such a pad may be weakened as at 30 (Fig. 4) for being torn apart from the stub end, the stub ends of all the checks remaining connected 80 together by the staple 5. Each of the checks will be provided with columns of figures indicative of a charge to be made, and some of these figures may lie closely adjacent the edges of the checks, as at 31, while others 85 may lie in the middle portion of the checks and more remote from the edges, as at 32. It will be noted that by means of the present invention the punch may be utilized either to provide a notch in the edge of the check, 90 as indicated at 33 or an aperture in the middle portion of the check as indicated at 34, the punched aperture in the latter instance having a continuous periphery.

Means are provided for retaining pads on 95 the plate 1, in exposed position so that the checks may be torn from the pads one by one, along the weakened lines, and in the present embodiment the pad retaining means includes an arm 35 upstanding from the 100 edge of the plate 1 and having a part 3 providing a clip overhanging said plate and projecting toward the opposite side of the latter. The part 3 is adapted to be received within the body of the pad 2, as for instance, 105 between two adjacent checks of the pad (Figs. 3 and 4) and at its inner end is provided with a finger 4 which projects from the part 3 toward the check connecting means 5, when the pad is in position on the 110

plate. The finger 4 may be an integral portion of the part 3 and is preferably bevelled and rounded so as to provide a wedge shaped finger which may be wedged between 5 superposed adjacent checks so as to secure a relatively firm grip on the pad without unduly separating the adjacent checks. The pad may be conveniently applied to the holder by sliding it along the plate 1 from 10 the left, Fig. 1, so that the part 3 and finger 4 are received between two adjacent checks, the bottom of the pad passing over a short upstanding stop lug 6, which lug in conjunction with the finger 4 will tend to restrain 15 the pad from longitudinal movement on the plate 1, the lug 6 cooperating with the stub at that side of the check connecting means 5 which is opposite the finger 4. By providing the check connecting means described 20 it will be noted that the number of checks in the pad is relatively immaterial; a pad with a large number of checks will be as readily held as a pad with a smaller number. The arms may be as long or as short 25 as required. In addition to the finger 4 it will be noted that the arm 35 is adapted to participate in retaining the pad on the plate 1, said arm 35 lying, if desired, closely alongside the lateral longitudinal margin of 30 the pad. To permit the ready introduction of the pad between the clip and the plate 1, the upper face of the stop lug 6 may be rounded, as illustrated, so as to provide an inclined face merging with the upper face 35 of the plate 1. In this wise the pad may readily be slipped into or out of operative position beneath the clip, by the exercise of a slight force.

When the pad is retained on the plate 1, 40 as described, the longitudinal lateral margin 36 thereof which is opposite the arm 35 is adapted to provide a wall of a chamber into which punchings, produced as hereinafter described are delivered by the punching operation, and to assist in preventing the punchings from flying from the instrument. The plate 1 has a lateral extension 37 which may be flush therewith and in integral part thereof. Upstanding from the outer end of 45 this extension is the die plate 9, which may be an integral flange bent from the plate 1 so as to face, but be spaced from, the lateral face, or wall 36, of the pad 2. This plate 9 may be commensurate in length with the 50 pad and provides a wall opposite the pad forming wall 36 of the chamber referred to. In the plate 9 is the die opening 11 which extends through this plate and communicates with the space between the plate 9 and 55 the pad 2 when the latter is in operative position. As illustrated, the die opening 11 is adjacent that end of the plate 1 whereat the stub of the pad is retained.

Cooperating with the die opening 11 is 60 the punch 14 which may be the properly

fashioned end of an oscillatable resilient spring metal tongue 13, which tongue is connected to the instrument at the end which is remote, or opposite to, the pad retaining end. In the present embodiment the tongue 70 13 is riveted on the outer face of the flange, or die plate, 9 and inclines upwardly preparatory to punching, but may be pressed downwardly to cause the punch 14 to cooperate with the die opening 11, as will be understood. An aperture 8 is provided for the attachment of one end of a suspending chain, the other end of the chain being intended to be attached to the belt of the operator, and it will be observed that the operative end of the tongue 13 extends in a direction away from the aperture 8, so that when the operator's hand, in the act of grasping the instrument, follows down the chain and slides into contact with the combined holder and punch, the holder slips readily into the hand without danger of the punch wounding the hand.

The cutting periphery of the die opening 11 and the cutting periphery of the punch 90 are each illustrated as continuous in outline, so that the punch and die will cooperate cleanly to sever a punching from the middle of a check, though it will be understood that the punching mechanism may be utilized to 95 punch the edge of the check, as indicated at 33, Fig. 7. In the embodiment illustrated the die opening 11 is angular in peripheral outline, preferably triangular, and the periphery of the punch is of similar outline 100 so as to cooperate to cleanly shear at each side of the triangle. In forming the punch a portion of the spring tongue 13 may be bent downwardly as at 38 and then back again outwardly but not quite to a plane 105 parallel to its former position, thereby forming a front punching finger 14, the forward end of this finger being bent downwardly in the form of a beak which is sharply pointed as at 15, the sides of this front finger having 110 shearing edges, the point of the finger being disposed to coact at the front corner, or angle, of the die opening 11. In rear of the front punching finger is the heel, or rear sharp punching finger which, in the embodiment illustrated, is provided by a separate angle piece one end 100 of which is riveted to the underface of tongue 13, the other end 101 lying against and being brazed to the arm 38 and projecting downwardly from the 115 base of the finger 14 and terminating in a plurality of sharp, or pointed punching fingers 102, 103, 104, to coact with the side, or base, of the die opening, to effect shearing. The full width of the end 101 of the angle 120 plate, including the fingers 102, 103, 104, is sharpened to provide a shearing edge to cooperate with the base of the die opening. The punching fingers above mentioned occur at intervals of the cutting periphery of 130

the punch, the finger 14 at the front and the plurality of fingers 102, 103, 104, at the rear, and the central rear punching finger 103 is so disposed that in the operation of punching it comes into contact with the check before the front punching finger does, being operatively in advance of the front punching finger. Furthermore the ends of the punching fingers are operatively in advance of the 10 shearing edge between adjacent punching fingers, and the central punching finger 103 is operatively in advance of the fingers 102 and 104.

The numeral 60 indicates a stripper, or 15 tongue, struck up from the metal of flange 9, bent forwardly and lying slightly above and adjacent the die opening 11 on the punch side of this flange. In this tongue is the opening 61 to permit the passage of the 20 punch to and from the die opening 11. Should the punchings tend to cling to the punch in its upward movement, they will be detached therefrom by the stripper. Furthermore the stripper prevents or limits rising 25 movement of the check with the punch.

It will be observed that the tongue 13 includes the punch supporting arm 38 which extends from the punch at an angle to the plane of the projection of the periphery 30 thereof from a point effectively wholly within said periphery so that the continuous periphery of the punch may effectively cooperate with the full periphery of the die opening 11 to effect the punching, the arm 38 following through the die opening 11, as much as may be required. In Fig. 4 a 35 detached check 39, is shown in position immediately after having been punched at its edge to provide a V shaped opening. The 40 numeral 17 indicates a lug, or upturned end of the plate 9, which operates as a check gauging means at one side of the die opening 11, this check gauging means cooperating to 45 gauge the check for being notched at its edge by the punch. The numerals 18 indicate a second check gauging means, being at the 50 opposite side of the die opening from the lug 17 and at a shorter distance from the die opening than the lug 17. The check 39 may 55 be slid beneath the punch 14 and the stripper 60 until it comes in contact with the lugs 18 whereupon it will be arrested in such position that the punching will be effected wholly within the edges of the check. 60 As illustrated the lugs 18 are integral parts of the tongue 13 and they are spaced from the die opening 11 a distance such that when a check lies on the plate 9 in engagement with lugs 18, it may be punched cleanly at 65 one of the amount figures remote from the edge of the check. At 19 are apertures in plate 9 for accommodating the play of the gauge lugs 18 and the lugs 18 have shoulders 62 and 63 to limit oscillation of the punch. 70 It will be understood that by means of the

described punching mechanism, a check may be punched to show a notch at its edge or to show only a punched aperture in the middle of the check or to show both a notch and an aperture as may be desired. The die plate 70 9 being smooth where the check is seated, as at 10, the check may readily be applied either against the gauge 17 or the gauge 18.

In some forms and in order to facilitate rapidly manipulating the punch, the tongue 75 13 instead of being smooth and flat on its upper face, may be provided with a seat for the finger, or thumb, which seat is distinguishable from immediate adjacent parts by the sense of touch. In the form illustrated 80 in Fig. 6, the seat is provided by a recess 40 in the surface of the tongue 13 adjacent the punching fingers. The recess may be formed by stamping the metal material of the tongue, and, if desired, by including an 85 aperture 41 in the tongue. The finger will enter the recess and the aperture and not only will the point of application of the punching pressure be indicated by touch, but the operating finger will in great measure 90 be prevented from slipping from the tongue.

It will be especially noted that the thrust of punching is substantially parallel to the faces of the checks and that the punching operation may be effected without pressing 95 on the checks in the pad. The pad is retained in longitudinal position on the plate 1 by means of the retaining finger 4 and the lug 6. The pad is spaced from the plate 9, and may be held in this spaced relation by 100 one or more pad stops, one of which is indicated at 7, being a lug struck up from the extension of plate 1, and another of which is indicated at 43, being a laterally projecting flange of the die plate 9, these pad stops 105 7 and 43 intervening the pad and the plate, or flange 9, and preventing the lateral margin of the pad from coming into contact with the body of the plate 9. The stop lug 7 may have a retaining finger 65 swaged to 110 a thin edge, for engaging between the checks adjacent the stub. This finger 65 need not be of sufficient length to engage the staple of the pad, and preferably is placed nearer the end 6 than is the finger 3. Thus the pad is retained within the outside lateral margins of the stiff material of the holder so that when the holder is grasped and squeezed for 115 operating the punch, there need be no pressure on the pad. By reason of the fact that the punch is at the lateral margin of the holder, it is in the most efficient position for effecting strong punching pressure when held in one hand. Inasmuch as all parts of the instrument may be and are preferably 120 made of sheet metal, it is desirable to turn the edge of the plate 1, to form a bead 44 at that edge which is opposite the die plate 9, and thus guard the hand in punching.

In Fig. 5 a somewhat modified instrument 130

is illustrated. Instead of employing one finger 4, two such fingers are employed, these fingers closely approximating each other at a point overhanging the central portion of 5 the plate 1, as indicated at 45 and 46. In this embodiment the fingers may be the ends of a split metallic loop 47, which may be riveted as at 48 to the under face of the plate 1. Also instead of providing a pad stop 10 7 by striking up a part of the plate 1, this stop may be provided by striking a lateral flange 20 from the die plate 9, as illustrated.

Since certain changes may be made in the 15 above article and different embodiments of the invention could be made without departing from the scope thereof, it is intended that all matter contained in the above description or shown in the accompanying drawing shall be interpreted as illustrative 20 and not in a limiting sense.

It is also to be understood that the following claims are intended to cover all of the generic and specific features of the invention herein described, and all statements of the 25 scope of the invention, which, as a matter of language, might be said to fall therebetween.

Having described our invention, what we claim as new and desire to secure by Letters Patent, is:

- 30 1. A check holding instrument including, in combination, a plate, adapted to be held in the hand and to serve as a removable support for a pad of connected checks, having a lateral extension with a flange upstanding 35 therefrom, means for retaining the pad in position, said retaining means including a pad stop integral with the material of the instrument disposed to intervene said flange and pad, means adapted to cooperate with 40 the stud end of the pad removably to retain the pad on said plate in exposed position to permit checks to be torn from the pad one by one, said flange having a die opening 45 therethrough adjacent the pad retaining end of the instrument communicating with the space between said flange and said pad, and an oscillatable tongue connected to the instrument adjacent that end opposite the pad retaining end having a punch beak adapted 50 to cooperate with said die opening to punch a check, said pad retaining means including a relatively thin retaining finger overlying said plate adapted to be received between checks of said pad at one side of the check connecting means of the pad, and an upwardly projecting stop lug on said plate adapted to cooperate with the pad on the opposite side of said check 55 connecting means.

2. A check holding instrument including, in combination, a plate, adapted to be held in the hand and to serve as a removable support for a pad of connected checks, having a lateral extension with a flange upstanding therefrom, means for retaining the pad in position, said retaining means including a pad stop integral with the material of 55 the instrument disposed to intervene said flange and pad, means adapted to cooperate with the stub end of the pad removably to retain the pad on said plate in exposed position to permit checks to be torn from the pad one by one, said flange having a die 60 opening therethrough adjacent the pad retaining end of the instrument communicating with the space between said flange and said pad, and an oscillatable tongue connected to the instrument adjacent that end opposite the pad retaining end having a punch beak adapted to cooperate with said die opening to punch a check, said pad retaining means including a relatively thin retaining finger overlying said plate adapted to be received between checks of said pad at one side of the check connecting means of the pad, and an upwardly projecting stop lug on said plate adapted to cooperate with the pad on the opposite side of said check connecting means, the upper face of said lug being inclined to the pad supporting face of said plate and adapted to ease movement of said pad out of cooperative relation to said finger.
- 65 3. A check holding instrument including, in combination, a plate, adapted to be held in the hand and to serve as a removable support for a pad of connected checks, having a lateral extension with a flange upstanding therefrom, means for retaining the pad in position, said retaining means including a pad stop integral with the material of the instrument disposed to intervene said flange and pad, means adapted to cooperate with the stub end of the pad removably to retain the pad on said plate in exposed position to permit checks to be torn from the pad one by one, including an arm, upstanding from said plate at the side of the pad opposite said flange, having a die 70 opening therethrough adjacent the pad retaining end of the instrument communicating with the space between said flange and said pad, and an oscillatable tongue connected to the instrument adjacent that end opposite the pad retaining end having a punch beak adapted to cooperate with said die opening to punch a check, said pad retaining means including a relatively thin retaining finger overlying said plate adapted to be received between checks of said pad at one side of the check connecting means of the pad, and an upwardly projecting stop lug on said plate adapted to cooperate with the pad on the opposite side of said check connecting means.

3. A check holding instrument including, in combination, a plate, adapted to be held in the hand and to serve as a removable support for a pad of connected checks, having a lateral extension with a flange upstanding therefrom, means for retaining the pad in position, said retaining means including a pad stop integral with the material of the instrument disposed to intervene said flange and pad, means adapted to cooperate with the stub end of the pad removably to retain the pad on said plate in exposed position to permit checks to be torn from the pad one by one, said flange having a die opening 90 therethrough adjacent the pad retaining end of the instrument communicating with the space between said flange and said pad, and an oscillatable tongue connected to the instrument adjacent that end opposite the pad retaining end having a punch beak adapted to cooperate with said die opening to punch a check, said pad retaining means including a relatively thin retaining finger overlying said plate adapted to be received between checks of said pad at one side of the check connecting means of the pad, and an upwardly projecting stop lug on said plate adapted to cooperate with the pad on the opposite side of said check connecting means.

3. A check holding instrument including, in combination, a plate, adapted to be held in the hand and to serve as a removable support for a pad of connected checks, having a lateral extension with a flange upstanding therefrom, means for retaining the pad in position, said retaining means including a pad stop integral with the material of the instrument disposed to intervene said flange and pad, means adapted to cooperate with the stub end of the pad removably to retain the pad on said plate in exposed position to permit checks to be torn from the pad one by one, said flange having a die opening 95 therethrough adjacent the pad retaining end of the instrument communicating with the space between said flange and said pad, and an oscillatable tongue connected to the instrument adjacent that end opposite the pad retaining end having a punch beak adapted to cooperate with said die opening to punch a check, said pad retaining means including a relatively thin retaining finger overlying said plate adapted to be received between checks of said pad at one side of the check connecting means of the pad, and an upwardly projecting stop lug on said plate adapted to cooperate with the pad on the opposite side of said check connecting means, the upper face of said lug being inclined to the pad supporting face of said plate and adapted to ease movement of said pad out of cooperative relation to said finger.

4. A check holding instrument including, in combination, a plate, adapted to be held in the hand and to serve as a removable support for a pad of connected checks, having a lateral extension with a flange upstanding therefrom, means for retaining the pad in position, said retaining means including a pad stop integral with the material of the instrument disposed to intervene said flange and pad, means adapted to cooperate with the stub end of the pad removably to retain the pad on said plate in exposed position to permit checks to be torn from the pad one by one, including an arm, upstanding from said plate at the side of the pad opposite said flange, having a die 100 opening therethrough adjacent the pad retaining end of the instrument communicating with the space between said flange and said pad, and an oscillatable tongue connected to the instrument adjacent that end opposite the pad retaining end having a punch beak adapted to cooperate with said die opening to punch a check, said pad retaining means including a relatively thin retaining finger overlying said plate adapted to be received between checks of said pad at one side of the check connecting means of the pad, and an upwardly projecting stop lug on said plate adapted to cooperate with the pad on the opposite side of said check connecting means.

- a part projecting toward said flange adapted for reception between checks of said pad, said projecting part having a wedging finger projecting toward the check connecting means at the stub end of the pad, said plate having a stop lug cooperative with the stub at the opposite side of the check connecting means from said finger to restrain longitudinal movement of the pad 5
- 10 on said plate, said flange having a die opening therethrough adjacent the pad retaining end of the instrument communicating with the space between said flange and said pad, and an oscillatable tongue connected to 75
- 15 the instrument adjacent that end opposite the pad retaining end having a punch beak adapted to cooperate with said die opening to punch a check. 75
5. A check holding instrument including, 20 in combination, a plate, adapted to be held in the hand and to serve as a removable support for a pad of connected checks, having a lateral extension with a flange upstanding therefrom, means for retaining the pad in 80
- 25 position, said retaining means including a pad stop integral with the material of the instrument disposed to intervene said flange and pad, means adapted to cooperate with the stub end of the pad removably to retain 85
- 30 the pad on said plate in exposed position to permit checks to be torn from the pad one by one, said flange having a die opening therethrough adjacent the pad retaining end of the instrument communicating with the 90
- 35 space between said flange and said pad, an oscillatable tongue connected to the instrument adjacent that end opposite the pad retaining end having a punch beak adapted to cooperate with said die opening to punch a 95
- 40 check, said die opening and said punch beak each having a continuous cutting periphery, and check gauging means at opposite sides of said die opening, that on one side being at a different distance from said die opening 100
- 45 from that on the other. 105
6. A check holding instrument, including in combination, a plate, adapted to be held in the hand and to serve as a removable support for a pad of connected checks, having 110
- 50 a lateral extension with a flange upstanding therefrom, means for retaining the pad in position, said retaining means including a pad stop integral with the material of the instrument disposed to intervene said flange 115
- 55 and pad, means adapted to cooperate with the stub end of the pad removably to retain the pad on said plate in exposed position to permit checks to be torn from the pad one by one, said flange having a die opening 120
- 60 therethrough adjacent the pad retaining end of the instrument communicating with the space between said flange and said pad, an oscillatable tongue connected to the instrument adjacent that end opposite the pad retaining end having a punch beak adapted 125
- 65 to cooperate with said die opening to punch a check, said die opening and said punch beak each having a continuous cutting periphery, and check gauging means at opposite sides of said die opening, that on one side being at a different distance from said die opening from that on the other, said tongue having a recess in its face providing a finger seat distinguishable by touch from adjacent parts of the tongue. 130
7. A check holding instrument including, in combination, a plate, adapted to be held in the hand and to serve as a removable support for a pad of connected checks, having a lateral extension with a flange upstanding therefrom, means for retaining the pad in position, said retaining means including a pad stop integral with the material of the instrument disposed to intervene said flange and pad, means adapted to cooperate with the stub end of the pad removably to retain the pad on said plate in exposed position to permit checks to be torn from the pad one by one, said flange having a die opening therethrough adjacent the pad retaining end of the instrument communicating with the space between said flange and said pad, an oscillatable tongue connected to the instrument adjacent that end opposite the pad retaining end having a punch beak adapted to cooperate with said die opening to punch a check, and a flexible suspender connected to the implement at the end opposite the pad retaining means. 135
8. A check holding instrument including, in combination, a plate, adapted to be held in the hand and to serve as a removable support for a pad of connected checks, means adapted to cooperate with the pad removably to retain the pad on said plate in exposed position to permit the checks to be torn from the pad one by one, a flange angularly disposed relatively to said plate and having a die opening therethrough, and check punching mechanism including a punch beak positioned for cooperation with said die opening to punch a check, said beak being disposed so that the thrust of punching is parallel to the faces of the checks of the pad on said plate, said pad being held in spaced relation to said flange and punching mechanism and cooperating to provide a chamber into which the punchings are projected through said die opening by said punching mechanism. 140
9. A check holding instrument including, in combination, a plate, adapted to be held in the hand and to serve as a removable support for a pad of connected checks, means adapted to cooperate with the pad removably to retain the pad on said plate in exposed position to permit the checks to be torn from the pad one by one, check punching mechanism carried by said plate including a die and a punch each having a continuous cutting periphery and an oscillatable punch 145

supporting arm extending from said punch at an angle to the plane of the projection of the periphery of the punch from a point wholly within said periphery.

- 5 10. A check holding instrument including, in combination, a plate, adapted to be held in the hand and to serve as a removable support for a pad of connected checks, means adapted to cooperate with the pad removably to retain the pad on said plate in exposed position to permit the checks to be torn from the pad one by one, check punching mechanism carried by said plate including a die and a punch each having a continuous cutting periphery and an oscillatable punch supporting arm extending from said punch at an angle to the plane of the projection of the periphery of the punch from a point wholly within said periphery,
- 15 20. the cutting peripheries of said die and punch being angular, a portion of the cutting periphery of said punch inclining to the plane of said die, said punch having a point to initiate punching.
- 25 11. A device of the character described including, in combination, a plate having a die opening with an angular continuous cutting periphery, a punch having a continuous cutting periphery adapted to cooperate with said die and a point extending transversely of the plane of said die to initiate punching, and a punch supporting arm extending from said punch at an angle to the plane of said periphery of the punch from a point wholly
- 30 35. within said periphery and check gauging means at opposite sides of said die opening, that on one side being at a different distance from said die opening from that on the other.
- 40 12. A device of the character described including, in combination, a plate having a die opening with an angular continuous cutting periphery, a punch having a continuous cutting periphery cooperative with said die and a point extending transversely of the plane of said die to initiate punching, and a punch supporting arm extending from said punch at an angle to the plane of the projection of said periphery of the punch from a
- 45 50. point wholly within said periphery, and check gauging means at opposite sides of said die opening, that on one side being at a different distance from said die opening from that on the other, said arm having a recess in its face providing a finger seat distinguishable by touch from adjacent parts of the arm.

- 55 13. A check holding instrument, including, in combination, a plate adapted to serve as a removable support for a pad of checks, means adapted to cooperate with the pad removably to retain the pad on said plate in exposed position to permit the checks to be removed one by one, and mechanism carried by said plate, adapted to punch an

opening intermediate the edges of a check, inducing a die opening, and a punch having a plurality of sharp punching fingers at intervals peripherally of the cutting periphery of the punch, and shearing edges so disposed as to cooperate with the periphery of said die opening to shear the check between said fingers.

14. A check holding instrument, including, in combination, a plate, adapted to be held in the hand and to serve as a removable support for a pad of connected checks, means adapted to retain a pad of connected superposed checks on said plate including a retainer member adapted to be wedged into position in the body of the pad, punching mechanism, carried at one side by said plate so that the thrust of punching is crosswise of and parallel to the faces of the checks of the pad, including a die opening having a closed angular periphery, and an oscillatable tongue carrying a punch adapted to cooperate with said die opening to punch a check, said punch having a plurality of sharp punching fingers at intervals peripherally of the cutting periphery of the punch, one of said punching fingers being disposed to coact with said die opening at an angle of the latter and another of said punching fingers being disposed to coact with the periphery of said die opening at a different point.

15. A check holding implement, including, in combination, a plate adapted to be held in the hand and to serve as a removable support for a pad of superposed connected checks, said plate having a laterally disposed retaining finger adapted to be wedged between checks of the pad at one side of the check connecting means of the pad, a stop lug at the opposite side of said check connecting means having an inclined upper face, and a flange opposite said retaining finger, a check punch mounted on said flange so that the thrust of punching is toward the side of said plate at which said retaining finger enters the body of said pad, lugs spacing said pad from said flange, said plate having a triangular die opening communicating with the space between said flange and pad, said punch including an oscillatable resilient tongue from which project a pointed punching finger to coact with a corner of said die opening and a plurality of pointed punching fingers to coact with a side of said die opening.

16. A check holding implement, including, in combination, a plate adapted to be held in the hand and to serve as a removable support for a pad of superposed connected checks, said plate having a laterally disposed retaining finger adapted to be wedged between checks of the pad at one side of the check connecting means of the pad, a stop lug at the opposite side of said check connecting means having an inclined upper

face, and a flange opposite said retaining finger, a check punch mounted on said flange so that the thrust of punching is toward the side of said plate at which said retaining finger enters the body of said pad, lugs spacing said pad from said flange, said plate having a triangular opening communicating with the space between said flange and pad, said punch including an oscillatable resilient tongue from which project a pointed punching finger to coact with a corner of said die opening and a plurality of pointed punching fingers to coact with a side of said die opening, one of said plurality of punching fingers being operatively in advance of said corner coacting finger.

17. A check holding implement, including, in combination, a plate adapted to be held in the hand and to serve as a removable support for a pad of superposed connected checks, said plate having a laterally disposed retaining finger adapted to be wedged between checks of the pad at one side of the check connecting means of the pad, a stop lug at the opposite side of said check connecting means having an inclined upper face, and a flange opposite said retaining finger, a check punch mounted on said flange so that the thrust of punching is toward the side of said plate at which said retaining finger enters the body of said pad, lugs spacing said pad from said flange, said plate having a triangular die opening communicating with the space between said flange and pad, said punch including an oscillatable resilient tongue from which project a pointed punching finger to coact with a corner of said die opening and a plurality of pointed punching fingers to coact with a side of said die opening, one of said plurality of punching fingers being operatively in advance of the others and of said corner coacting finger.

18. A check holding instrument, including, in combination, a plate adapted to be held in the hand and to serve as a removable support for a pad of superposed connected checks, said plate having a laterally disposed retaining finger adapted to be wedged between checks of the pad at one side of the check connecting means of the pad, a stop lug at the opposite side of said check connecting means having an inclined upper face, and a flange opposite said retaining finger, a check punch mounted on said flange so that the thrust of punching is toward the side of said plate at which said retaining finger enters the body of said pad, lugs spacing said pad from said flange, said plate having a triangular die opening communicating with the space between said flange and pad, said punch including an oscillatable resilient tongue from which project a pointed punching finger to coact with a corner of said die opening and a sharp

punching finger to coact with a side of said die opening, and a stripper disposed adjacent said die opening on the punch side of said flange.

19. A check holding instrument, including, in combination, a plate adapted to serve as a removable support for a pad of checks, a pad clip overlying said plate and spaced therefrom to permit the pad to rest on said plate with one or more of the checks clasped between said clip and plate adjacent the stub end of the pad, a stop lug upwardly projecting from said plate on the stub side of said clip having an inclined upper face, said plate having a side flange having a die opening, and an oscillatable tongue having a punch to cooperate with said die opening, and a spacing lug cooperating with said pad to support it in spaced relation with reference to said flange.

20. A check holding instrument, including, in combination, a plate adapted to serve as a removable support for a pad of checks, a pad clip overlying said plate and spaced therefrom to permit the pad to rest on said plate with one or more of the checks clasped between said clip and plate adjacent the stub end of the pad, a stop lug upwardly projecting from said plate on the stub side of said clip having an inclined upper face, said plate having a side flange having a die opening, and an oscillatable tongue having a punch to cooperate with said die opening, said flange having a stripper struck therefrom, disposed on the punch side of said die opening and having an opening for the passage of said punch, said tongue having a check gauge at a predetermined distance from said die opening.

21. A check holding instrument, including, in combination, a plate adapted to serve as a removable support for a pad of checks, a pad clip overlying said plate and spaced therefrom to permit the pad to rest on said plate with one or more of the checks clasped between said clip and plate adjacent the stub end of the pad, a stop lug upwardly projecting from said plate on the stub side of said clip having an inclined upper face, said plate having a side flange having a die opening, an oscillatable tongue having a punch to cooperate with said die opening, said flange having a stripper struck therefrom, disposed on the punch side of said die opening, and having an opening for the passage of said punch, said tongue having a check gauge at a predetermined distance from said die opening, said gauge having shoulders adapted to cooperate with said flange to limit the oscillation of said tongue.

In testimony whereof we affix our signatures.

EDWARD KIRBY BOTTLE.
JAMES W. ANDERSON.
